UNITED STATES PATENT OFFICE

WALTER E. KING, OF HOUSTON, TEXAS

WELL SCREEN

Application filed January 15, 1926. Serial No. 81,448.

This invention relates to new and useful improvements in well screens and has more particular relation to that type of well screens which embody perforated pipe with screening elements inserted and secured within the perforations, said type of screens being commonly known as "button screens."

One object of the invention is to provide a screen of the character described, which is 10 very simple in construction and may be cheaply produced and which is very durable in use.

Another object of the invention is to provide a screen of the character described embodying a screening button which, when inserted into the perforation of the pipe will form its own means of engagement with the metal of said pipe.

A further feature of the invention resides 20 in the provision of a well screen embodying a button which is so formed that, when inserted into the perforation of the screen pipe, will interengage with said metal to anchor itself in said perforation.

25 With the above and other objects in view the invention has particular relation to certain novel features of construction, arrangement of parts, and use, an example of which is given in this specification and illustrated 30 in the accompanying drawings, wherein Figure 1 shows an enlarged outside view of the screening button employed.

Figure 2 shows a side view of said button showing a central or knurled section with 35 reduced cylindrical sections at the ends.

Figures 3 and 4 show end and side views respectively of a screening button which is knurled or toothed from end to end.

40 Figure 5 shows an outer end view of another type of screening button.

Figure 6 shows a side view thereof showing one end of this type of button reduced and blank and with the knurling parallel with the axis of the button.

45 Figure 7 shows a longitudinal sectional view of the button in place.

Figure 8 is an end view of the type of button shown in Figure 7.

50 Figures 9 and 10 show outer end and side views respectively of a type of button having

a single inlet therethrough which preferably flares inwardly.

Figure 11 shows a fragmentary elevational view of a well screen in which the screening buttons are employed and shown partly in 55 section.

Referring now more particularly to the drawings, wherein like numerals of references designate similar parts in each of the figures, the numeral 1 designates a pipe which 60 is provided with the perforations 2. The numeral 3 designates a screening button whose inner and outer ends are reduced as at 4 and 5 and blank, said button being knurled between said blank sections, as at 6. The 65 blank extension 4, employed in the form shown in all of the figures except 3 and 4, is provided to fit well into the perforation as an easy means for starting and will also act as a guide, or pilot when the button is being 70 forced into the perforation under pressure, or by a direct blow, as with a hammer. The peripheral knurling 6, may be straight, or parallel with the axis of the button, as in Figure 6, or helical, as in Figures 2, 4, and 10. 75

This knurling may also be of some other form, the preferred forms only being shown. The diameter of the knurled portion of the button is somewhat greater than the diameter of the perforation. As a consequence 80 upon being forced, or driven into the perforations 2 of the tube 1, the crests of the knurling will cut, or plough, into the metal of which the pipe 1 is made and preferably the buttons, or particularly the knurling thereof 85

are to be harder than the metal of the pipe and capable of cutting into it. As the buttons are forced into the perforations they will displace metal which will flow into the channels 7, between the teeth of the knurled portions. The bottoms of these channels are countersunk beneath the surface of the reduced end 4, of Figures 2, 6 and 10 forming an abutting shoulder 8 and are likewise countersunk beneath the blank portion 5, Figures 95 1 and 2, thus forming the abutting shoulders 8'. As the displaced metal is forced into said channels it will engage behind the shoulders 8 to lock the button against withdrawal outwardly.

When the form shown in Figures 1 and 2 is employed the blank section 5 will tend to force the metal displaced by the knurling 6 back into its original position, thus forming 5 an opposing shoulder against which the shoulder 8 engages and the screen buttons are thus locked against movement in either direction.

The type of screen button shown in Figure 10 4 has not the reduced blank end for entering the perforation, but is slightly beveled at its entering end, its helical peripheral knurling will cut into the metal around the perforation and will retain its position thereby in the 15 perforation, by friction.

No particular type of knurling is indispensable. Preferably helical or straight peripheral teeth will be employed, as shown, but other types of peripheral knurling on the 20 screen button may be employed, if desired.

The outer ends of the buttons are provided with slits, as 9, in all of the figures except 9 and 10. These slits are provided for the inlet of surrounding fluid and are common to 25 button screens now in common use.

The type of button shown in Figures 9 and 10 is of novel formation, having the port 10 therethrough, which if desired may be flared inwardly as at 11. It often happens that 30 screens are desired formed of large sections of pipe with very small perforations that are impractical to drill. In such case the pipe may be drilled with larger perforations and the buttons shown in Figures 9 and 10 then 35 driven into said perforations.

Attention is here called to the fact that when the pipe is perforated no subsequent operation is necessary for inserting the buttons. In other types of button screens the 40 perforations must be counterbored to form shoulders against which the screen buttons are set, or said buttons are threaded into the perforations. These two are the most common types of button screens now in use.

45 Attention is further called to the fact that in button screens heretofore made the buttons are of soft metal such as brass or bronze, while in the screen herein described the buttons are formed of hard steel so that they 50 will withstand the abrasive action of sand, which they are intended to exclude from the well, and should be noncorrosive to withstand the action of salt water, acids and other corrosive agencies so common in many wells.

55 I have shown only two forms of knurling to form means for holding the buttons in the pipe. It is apparent that the knurling of the buttons may be differently formed to 60 accomplish the same purpose and I do not wish to be understood as having limited myself to the particular form shown and I reserve the right to make such structural changes as will not depart from the scope of 65 the appended claims.

What I claim is:—

1. A well screen composed of a tubular section, having perforations, screen buttons in said perforations, the outer ends of said buttons being provided with slits, the inner and outer ends of said buttons being reduced and blank, and the periphery of the buttons between such blank sections being provided with substantially parallel teeth. 70

2. A well screen composed of a tubular 75 section, having perforations, screen buttons in said perforations, the outer ends of said buttons being provided with slits, the inner and outer ends of said buttons being reduced and blank and the periphery of the buttons 80 between such blank sections being provided with substantially parallel teeth, said teeth having sharp crests and their inner ends being beveled inwardly.

3. A well screen button having screening 85 openings at its outer end and reduced at its inner end, said reduced portion being blank, approximately parallel teeth on the periphery of the button and extending longitudinally thereof the inner ends of the teeth being inwardly beveled. 90

4. In combination with a screen pipe having uniform diameter openings therein, a strainer button for each of said openings, said button having peripheral projections 95 thereon of greater diameter than that of said openings, whereby said projections may deform the faces of said openings when said buttons are driven in place.

In testimony whereof I have signed my 100 name to this specification.
